J. L. GOBEILLE.

COOKING STOVE OR RANGE.

No. 18,012.

Patented Jan. 10, 1888.

UNITED STATES PATENT OFFICE.

JOSEPH LEON GOBEILLE, OF CLEVELAND, ASSIGNOR TO THE FOSTER STOVE COMPANY, OF IRONTON, OHIO.

DESIGN FOR A COOKING STOVE OR RANGE.

SPECIFICATION forming part of Design No. 18,012, dated January 10, 1888.

Application filed August 3, 1887. Serial No. 246,067. Term of patent 7 years.

To all whom it may concern:

Be it known that I, JOSEPH LEON GOBEILLE, a citizen of the United States, residing at Cleveland, in the county of Cuyahoga and State of Ohio, have invented and produced a new and original Design for Domestic Cooking Stove or Range; and I do declare the following to be a full, clear, and exact description of the invention, reference being had to the accompanying drawing, which forms a part of this specification.

This design includes the ornamentation of the several parts of a domestic cooking stove or range, and is illustrated in the accompanying drawing, which forms a part of this specification, and in which the figure is a perspective view of my design for a stove.

As shown in the drawing, the oven-door A has a central figure surrounded by a border of uniform width composed of and ornamented by a series of shallow contiguous depressions of polygonal form, producing a cellular appearance. The central figure is composed of a rectangular portion with smooth convex sides and edges. In the center of said figure is a cross formed by a depressed ground of small circles presenting a mottled appearance. The parts outside the cross are of contrasting color, and are ornamented by a depressed line-tracing of the character shown. To one side of the said rectangular figure is an angular portion composed of a ground presenting a mottled appearance and carrying a raised vine-like and floral figure and a knob for opening the door. A fillet of the style shown at α^2 follows the contour of the said border both on the outside and on the inside.

In shape the door is larger at one side than at the other, and above the smaller end of said door is the fire-door, of a shape corresponding to a square with one corner cut off. The ornamentation of this door is substantially the same as that of the oven-door. A border similar to the one on the large door surrounds a central frame of contrasting color inclosing a ground which presents a mottled appearance, and a vine-like and floral figure thereon. This border constitutes one of the leading features of my design. It appears on both the stove-doors and also on the reservoir. The front

and sides of the stove, where not ornamented, are smooth. On each side of the large door is a floral ornament in the form of a narrow vertical band of leaves extending upwardly.

The reservoir is placed at the rear of the stove proper, and has a skirting the contour of which is shaped as shown. A raised panel is placed in the center of the end of the reservoir-easing, (which end corresponds to the side of the stove,) and consists of a rectangular central frame of polished metal containing a tracing of leaves and tendrils somewhat in the shape of the figure 8 on a ground presenting a mottled appearance. Outside the central frame is a border of uniform width composed of and ornamented by a series of shallow contiguous depressions of polygonal form similar in appearance to the border on the doors. A narrow fillet of the character shown surrounds the said panel, the ground upon which it rests being smooth and unornamented, except near the bottom, where a raised floral design is placed.

The shelf below the oven-door is ornamented by tracery of vine-like character and a contrasting smooth border surrounded by lines placed at right angles to one another. The hearth-plate is surrounded by a line tracery having intersecting lines at the corners and leaf design on the lines intermediate the corners and depressed letters inclosed within the said line tracery. The edge of the said hearth-plate is smooth, and by contrast with the other parts produces the appearance of a broad band of shining material. The said contrasting edge extends all around the hearth-plate or fire-bottom, and abruptly rises at F and again bends horizontally at G, terminating finally under the smaller door. Above the hearth-plate are two doors, both provided with a register, the lower or grate door having three small windows above its register. The appearance of this door is almost square, with heavy beveling on three sides and a ledge, as shown, on the bottom. The ornamentation consists of a beading shown and the raised designs on the sides of the register-openings. The upper door is placed on a chute, and is set at an angle of forty-five degrees to the plane of the top plate. The ornamentation consists of floral designs sur-

rounding the register-openings and others of the character shown on the register-plate.

The design for the lower portion of the stove embraces a skirting having an irregular or undulating lower edge comprising the inclines *m*, the rounded parts *n*, and the level center part, *o*. The skirting on the four sides of the stove extends from leg to leg, and where it meets the leg it forms an angle or point, *p*. The ornamentation on the ends of the skirting comprises a star and florets and leaves placed on a smooth ground. Above the inclined contour *m m* are depressed portions having raised vine-like designs, with broad leaves *m' m'* on a ground presenting a mottled appearance, the same style of designs being placed over the rounded parts and a double leaf, as shown in the rectangular frame *D'*. A scalloped fillet extends from *r* to *r'*. The edges of the legs are indented on their upper portions to correspond with the pointed ends of the skirting, and are ornamented by a raised shell-like figure surrounded by a smooth border, the lower part of the legs being curved inwardly and then flaring outwardly, and a leaf design being placed on the foot, a plain ground on the concave part, and a smooth band passing down the sides of each leg.

What I claim is—

- 30 1. In a design for a stove, the oven-door comprising an unbroken border of uniform width composed of a series of irregular cell-like contiguous depressions, the rectangular panel bearing the cross-like ornamentation and surrounded by the line tracery, and the adjacent angular portion with the vine-like design thereon, substantially as shown.
- 35 2. In a design for a stove, the fire-door *B*, comprising the border *a'*, the centrally-located

bead *b'*, and the raised vine-like figure *c* there- 40 in, substantially as set forth.

3. The design for the reservoir, comprising the skirting *a'*, the raised vine-like figure *b'*, the panel *c'*, and the center *c'*, substantially as described and illustrated. 45

4. The design for a stove, the body thereof comprising the base having a skirting and legs, the oven-door and fire-door of irregular shape, and the reservoir, each having a central panel surrounded by a border of uniform 50 width composed of irregular cell-like contiguous depressions, the front end with the grate-door and the draft-door above the hearth plate and the top, as described and shown.

5. In a design for a stove, the leg-base comprising the ornamental skirting pointed at 55 each end, and the ornamentation and configuration of the legs, the said legs having upper edges indented, and the shell-like figures thereon, substantially as set forth. 62

6. In a design for a stove, the legs thereof having the edges indented at their upper portions, presenting the appearance of two triangles joined at their open apices and surrounded by a border of uniform width, and 65 having within this border a raised shell-like ornamentation, and the lower outward portion of the legs being surrounded by a smooth band inclosing a leaf-like ornamentation and having a mottled field above, substantially as de- 70 scribed and illustrated.

In testimony whereof I affix my signature in presence of two witnesses.

JOSEPH LEON GOBEILLE.
